UNITED STATES PATENT OFFICE.

JOHN G. KELLER, OF MILWAUKEE, WISCONSIN, ASSIGNOR TO THE VILTER MANUFACTURING COMPANY, OF MILWAUKEE, WISCONSIN, A CORPORATION OF WISCONSIN.

PLATE-VALVE CONSTRUCTION.

1,350,101.

Specification of Letters Patent. Patented Aug. 17, 1920.

Application filed March 17, 1919. Serial No. 283,194.

To all whom it may concern:

Be it known that I, JOHN G. KELLER, a citizen of Switzerland, and resident of Milwaukee, in the county of Milwaukee and 5 State of Wisconsin, have invented new and useful Improvements in Plate-Valve Construction, of which the following is a description, reference being had to the accompanying drawings, which are a part of this 10 specification.

This invention relates to improvements in plate valve construction more particularly, although not solely, adapted for medium and high speed gas and air compressors.

15 It is one of the objects of the present invention to provide a plate valve construction in which one or a plurality of plate valve members may be positioned in a valve seat casing in such a manner as to cause said 20 valve to operate silently and be dependable and efficient at medium and high speeds.

A further object of the invention is to provide a plate valve construction in which the 25 valve members are interchangeable for inlet or outlet control and are efficient under continuous and severe conditions.

A further object of the invention is to prevent any part from accidentally falling into 30 the cylinder in which it is used, thereby avoiding accidents.

A further object of the invention is to provide a plate valve construction in which the 35 valve members are formed of comparatively thin steel disks or rings which are yieldingly held on their seat portions by coiled springs formed of flat material which have circumferential continuous contact with the valve 40 members, thus forming an equal pressure on the entire surface of the valve members.

A further object of the invention is to provide a plate valve construction in which the 45 valve spring guide member is formed with recessed portions for holding the valve members and springs, thereby forming noiseless cushioning means for the lift of the valve plates.

A further object of the invention is to provide a plate valve construction in which the 50 valve seat casing may be formed to accommodate any desired number of valve members which are independently guided and operable.

55 A further object of the invention is to

provide a plate valve construction in which the parts are of simple construction, strong and durable and well adapted for the purpose described.

With the above and other objects in view 60 the invention consists of the improved plate valve construction and its parts and combinations as set forth in the claims and all equivalents thereof.

In the accompanying drawing in which 65 the same reference characters indicate the same parts in all of the views:

Figure 1 is a top view of the improved plate valve construction;

Fig. 2 is a transverse sectional view there- 70 of taken on line 2—2 of Fig. 1; and

Fig. 3 is a top view of the valve plate construction with the upper valve seat member removed.

Referring to the drawing, the numeral 5 75 indicates one form of the improved valve plate construction which is particularly adapted for air and gas compressor use, and which comprises an upper valve seat casing member 6, a lower valve plate casing 80 7, inner and outer plate valves 8 and 9 and spring members 10 and 11. The upper and lower members 6 and 7 are of circular form and are connected together by a screw or bolt 12 which extends axially through the 85 upper member and is threaded into the lower member. The peripheral portions of the casing members preferably overlap as indicated by the numeral 13 to form a joint and to properly align the parts and prevent 90 lateral movement.

The upper member 6 is formed with a plurality of segmental inlet openings or passageways 14 extending vertically therethrough and the inner face of the said member is provided with circumferential grooves 15 which extend around the said face on opposite sides of the inner and outer circumferential lines of openings and form valve 100 seats 16 and 17 therebetween.

The lower casing member is provided with a plurality of inner and outer segmental outlet openings or passageways 18 and 19 which extend vertically therethrough. Said openings 18 and 19 extend in circumferential 105 lines around the member and are staggered radially with relation to the openings of the upper member and the inner face portion of said lower member between the circumferential lines of openings is provided 110

with inner and outer annular spring receiving recesses 20 and 21. The spring members 10 and 11 before mentioned are seated in these annular recesses and bear upwardly 5 against the ring or disk-like valves 8 and 9 also before mentioned.

The springs are preferably formed of comparatively thin flat strip spring metal bent edgewise into convolute shape to bear evenly 10 against the lower surfaces of the ring valves and provide a quick snappy action therefor.

The valves are preferably of ring shape and formed of thin hardened material having ground seat engaging faces 8' and 9' 15 which movably bear against the seats 16 and 17. Said valves are of greater width than the spring recesses 20 and 21, and the inner portion of the lower member is formed with valve recesses 22 and 23 to accommodate 20 said valve and permit the play thereof. The valve recesses also provide for the passage of the fluid medium from the openings 14 around the valves 8 and 9 and through the openings 18 and 19.

25 Extension portions 25 projecting from the inner face of the lower casing member closely fit the inner peripheral edges of the ring valves and guide said valves in their reciprocations and vibrations.

30 As the valve members for a given size opening are all of the same size and shape, they may be interchangeably used for both inlet and outlet openings.

While the drawing shows and the specification describes an upper and a lower casing member, it is to be understood that the terms are only used for convenience of description, as the plate valve will also operate as well in an inverted position. It is 35 also to be understood that one or any number of concentric valve members may be used in the same casing without departing from the spirit and scope of the invention.

40 From the foregoing description it will be seen that the plate valve is of very simple construction, and is well adapted for the purpose described.

45 What is claimed as my invention is:

1. A valve construction, comprising a two 50 part casing member forming a tight peripheral closure and having passageways extending axially therethrough, one of said member parts having an annular valve seat and the other member having an annular 55 valve recess and an annular spring recess, a flat ring-shaped valve within the valve recess and engaging the valve seat, a coiled spring approximately the same diameter as the valve positioned within the spring recess for holding the valve yieldingly in closed 60 position, and means for holding the two parts of the two part casing member together.

2. A valve construction, comprising a two 65 part casing member forming a tight periph-

eral closure and having passageways axially extending therethrough, one of said member parts having an annular valve seat and the other member having an annular valve recess and an annular spring recess, a flat 70 ring-shaped valve within the valve recess and engaging the valve seat, a coiled spring formed of flat material positioned within the spring recess for holding the valve yieldingly in closed position, and means for holding the two parts of the two part casing member together.

3. A valve construction, comprising a two part casing member forming a tight peripheral closure and having a plurality of passageways extending axially therethrough, the passageways in one of the member parts being radially staggered with relation to the passageways of the other member part, one of said member parts having an annular valve seat on its inner face and on opposite sides of the passageways extending through said part, the other member part having an annular valve recess and an annular spring recess between the passageways 80 extending through said part, said last mentioned member also having inwardly extending valve guide extensions, a flat ring-shaped valve within the valve recess and engaging the valve seat, the inner edge of said 85 valve engaging said guide extensions, a coiled spring formed of flat material positioned within the spring recess for yieldingly holding the valve in closed position, and means for holding the two parts of the 100 two part casing member together.

4. A valve construction, comprising a two-part casing member forming a tight peripheral closure and having staggered passageways extending therethrough and also 105 having a plurality of concentric valve seats in one of its parts, the other part of said member having concentric valve recesses and concentric spring recesses, flat ring-shaped valves concentrically mounted in 110 said valve recesses and engaging the valve seats, coiled springs of flat material concentrically positioned within the spring recesses and engaging the valves, and means for holding the two parts of the two part 115 members together.

5. A valve construction, comprising a two-part casing member forming a tight peripheral closure and having staggered passageways extending axially therethrough 120 and also having a plurality of concentric valve seats in one of its parts, the other part of said member having concentric valve recesses and concentric spring recesses, a plurality of flat ring-shaped valves positioned concentrically in the valve recesses and engaging the valve seats, a plurality of coiled springs formed of flat material and positioned within the spring recesses 125 concentrically with relation to each other and 130

- engaging the valves, and a screw extending through one of the casing parts and threaded into the other part for holding the two parts of the two part member together.
- 5 6. A valve construction, comprising a two-part casing member forming a tight peripheral closure and having staggered passageways extending axially therethrough and also having a plurality of concentric 10 valve seats in one of its parts, the other part of said member having concentric valve recesses and concentric spring recesses, a plurality of flat ring shaped valves positioned concentrically in the valve recesses and en-
- gaging the valve seats, and a plurality of 15 coiled flat springs formed of flat material positioned within the spring recesses concentrically with relation to each other and engaging the valves, said recesses forming cushion pockets for the compression of the 20 several rings of the springs, thereby retarding or cushioning the flat ring shaped valves positioned concentrically in the valve recesses.
- In testimony whereof, I affix my signature.

JOHN G. KELLER.
